TELEVISION SYSTEM

Eric Lawrence Casling White, Hillingdon, Middlesex, England, assignor to Electric & Musical Industries Limited, Hayes, Middlesex, England, a company of Great Britain

Application May 10, 1939, Serial No. 272,830
In Great Britain May 18, 1938

4 Claims. (Cl. 178—7.1)

This invention relates to television systems and has particular reference to methods of obtaining automatic gain or volume control.

The invention is an improvement in or a modification of the invention set forth in the specification of United States application Ser. No. 141,917, filed May 11, 1939, in which a method of obtaining a rapidly acting automatic gain control as required for example in aircraft television systems is described, although the method is applicable to television systems generally. In carrying out the method of United States application Ser. No. 141,917, filed May 11, 1937, the waveform transmitted is a carrier wave modulated by picture signals and includes sets of both whiter than white and blacker than black signal pulses which occur at predetermined intervals, and the receiver is provided with an automatic gain control system which is designed to be responsive to the difference between the amplitude of said signal pulses, the receiver being also provided with a synchronizing system which is designed to be responsive to one set of the signal pulses. The blacker than black pulses constitute line synchronizing signals and each of such pulses forms a portion of a double pulse, the other portion of which constitutes one of the whiter than white pulses. The carrier wave is also modulated by frame synchronizing signals which modulate the carrier wave in the whiter than white sense, the frame signals being interrupted by the line synchronizing signals in the blacker than black sense so that automatic gain control potentials and line synchronizing signals can be obtained during the occurrence of the frame synchronizing signals.

According to the present invention, a modification of the invention set forth in the specification of United States application Ser. No. 141,917 filed May 11, 1937, consists in modulating the transmitted carrier wave with frame synchronizing signals in the blacker than black sense. In order to eliminate at the receiver undesirable effects due to the pulses which modulate the carrier wave in the whiter than white sense, such pulses are suppressed by mixing them with the line synchronizing signals which are separated, delayed and/or broadened for this purpose.

In a particular television transmitting and receiving system embodying the invention the waveform sent out by the transmitter is a carrier wave modulated by picture signals in such a sense that an increase in picture brightness is represented by an increase in carrier amplitude, said waveform including blacker than black line and frame synchronizing signals and whiter than white

auxiliary signals and wherein the receiver is provided with an automatic gain control system which is designed to be responsive to the absolute amplitude of said whiter than white auxiliary signals.

In order that the invention may be more clearly understood and readily carried into effect a waveform modulated in accordance with the invention will now be more fully described by way of example with reference to the drawing filed with the specification in which

Fig. 1 shows such a waveform, and

Fig. 2 shows a circuit arrangement for preparing the line synchronizing signals to effect suppression of the gain controlling pulses.

If the waveform described in the specification of application Ser. No. 141,917 filed May 11, 1937, is changed so that the frame synchronizing pulses modulate the carrier wave in the blacker than black sense without other modification, a waveform results having the disadvantage that the line synchronizing pulses are interrupted by the frame synchronizing pulses and this is apt to cause disturbance in the line scanning at a receiver. An improvement is effected if the same step is adopted and in addition the automatic gain control pulses which modulate the carrier wave in the whiter than white sense are made to precede instead of to follow the line synchronizing pulses which modulate the carrier wave in the blacker than black sense. In this case the trailing edge of a gain control pulse will coincide with the leading edge of the line synchronizing pulse and since the automatic gain controlling pulses continue throughout the frame synchronizing pulses, the line scanning oscillator at the receiver will continue to be synchronized by the trailing edges of the automatic gain controlling pulses.

Since the automatic gain control pulses occur before the line synchronizing pulses, they result in a bright vertical bar appearing on the extreme right-hand edge of the received picture and this can be easily masked off. However, this does represent a loss of time during which picture signals could otherwise be transmitted and the waveform shown in Fig. 1 of the accompanying drawing overcomes this disadvantage.

Referring to Fig. 1, the waveform shown is for a line frequency of 10,000 per second, and it will be necessary that the automatic gain control pulses 1, which are of 10 micro-seconds duration, follow the line synchronizing pulses 2 as in the waveform described in the specification of application Ser. No. 141,917 filed May 11, 1937, the

duration of these line pulses being 5 micro-seconds. The frame synchronizing pulses 3 consist of 10 to 20 broadened line synchronizing pulses but with the automatic gain control pulses continuing through them. The picture signals 4, the duration of each line of which is 85 micro-seconds, are prevented from coming below a level represented by the line 5 which is of the order of 30% of the peak carrier wave output, and it is also convenient but not necessary to limit the upward excursions of the picture signals to about 90% as represented by the dotted line 6. 100% modulation of the carrier wave is represented by the line 7. The picture signals are suppressed to the 30% level 5 during the period of the frame synchronizing pulses.

The effect of the automatic gain control pulses of Fig. 1 on the received picture, which would be to brighten the end of the return stroke and the beginning of the working stroke, can be suppressed by separating the synchronizing pulses, delaying them by an amount not quite equal to their width, broadening them to a breadth slightly greater than the automatic gain control pulses and mixing them in negative sense with the picture signals.

A circuit arrangement for effecting the delaying and broadening of separated line synchronizing pulses is shown in Fig. 2. The separated negative line synchronizing pulses are applied to the terminals 8 between which and a diode valve D_1 is a network giving an initial delay t_1 . The delays introduced by the following networks are each equal to t_2 and less than the width of the original pulse. These delay networks are connected to diode valves D_2 , D_3 and D_4 , the anodes of which are connected together and with that of D_1 . The output from the diodes is passed to a valve V , the output from which consists of delayed and broadened positive pulses.

In operation, the grid of the valve V is maintained negative so long as incoming pulses are applied through the delay network to any of the diodes D_1 to D_4 . It should be arranged that the amplitude of the incoming line synchronizing pulses is sufficient to cause the valve V to be shut off so that the waveform of the output is regular.

Although four diodes are shown, any number n greater than one may be used. The width of the output pulse will be increased by $(n-1)t_2$. Thus, if the width of the line synchronizing pulse is t_s and that of the automatic gain control pulse is t_g , it must be arranged that t_s is greater than t_1 and $t_1 + (n-1)t_2$ is greater than $t_s + t_g$. The delayed and broadened pulse obtained from

the valve V will overlap the automatic gain control pulse on both sides and will therefore suppress it if mixed in the negative sense.

The waveform described possesses the advantages that all the positive automatic gain control pulses are equal in length so that design of a rapidly acting automatic gain control circuit at the receiver is facilitated and it is not necessary to arrange for blacking out the frame pulse at the receiver.

While in the waveform described the line synchronizing pulses have been shown to be shorter than the automatic gain control pulses, they may if desired be of the same length or longer than the automatic gain control pulses. In either of these latter cases, the suppressing pulses may be obtained merely by applying the line synchronizing pulses to a delay network.

What I claim is:

- 20 1. In a television system wherein line and frame synchronizing impulses of the same polarity are transmitted between sets of video signals, and wherein a signal of opposing polarity is transmitted after each line synchronizing signal, the method which comprises the steps of separating the synchronizing pulses, delaying the pulses by an amount differing from their duration, broadening the pulses to a breadth slightly greater than the width of the pulses having an opposing polarity thereto, and mixing the pulses in a negative sense with the video signals.
- 25 2. In a television transmitting system wherein automatic volume control signals are transmitted at a time adjacent the transmission of line synchronizing signals which are of opposite polarity thereto, and in which frame synchronizing signals are transmitted of the same polarity as the line synchronizing signals, means for separating said synchronizing pulses, means for delaying the line synchronizing pulses, means associated with said delaying means for broadening said line synchronizing pulses and means for mixing said pulses with the video signals.
- 30 3. Apparatus in accordance with claim 2, wherein the broadened line synchronizing pulses are mixed with the video signals in a negative sense.
- 35 4. Apparatus in accordance with claim 2, wherein said means for broadening the line synchronizing signals comprises a plurality of delay network means serially connected, each of said delay network means having a diode connected substantially across the terminals thereof.
- 40 5. Apparatus in accordance with claim 2, wherein the broadened line synchronizing pulses are mixed with the video signals in a negative sense.
- 45 6. Apparatus in accordance with claim 2, wherein the broadened line synchronizing pulses are mixed with the video signals in a negative sense.
- 50 7. Apparatus in accordance with claim 2, wherein the broadened line synchronizing pulses are mixed with the video signals in a negative sense.
